[57] CLAIM

I claim the ornamental design for a power golf bag carrier, as shown and described.

DESCRIPTION

FIG. 1 is a perspective view of power golf bag carrier showing my new design.

FIG. 2 is a left side view thereof.

FIG. 3 is a right side view thereof.

FIG. 4 is a front elevation thereof.

FIG. 5 is a rear elevation thereof; and,

FIG. 6 is a top plan view thereof.
